UNITED STATES PATENT OFFICE.

FREDERICK BEND, OF BROOKLYN, ASSIGNOR TO BUCHANAN & LYALL, OF NEW YORK, N. Y.

DESIGN FOR A CARPET.

SPECIFICATION forming part of Design No. 14,184, dated July 31, 1883.

Application filed June 21, 1883. Term of patent 7 years.

To all whom it may concern:

Be it known that I, FREDERICK BEND, of Brooklyn, in the county of Kings and State of New York, have invented a new Design for Carpets, of which the following is a full, clear, and exact description.

In this design there are stripes of different colors running longitudinally of the carpet, and there are rows of twilled lozenge-shaped patterns placed diagonally and repeated, the whole forming a peculiar ornamental design for carpets of this class.

In the photograph annexed, the stripes *a b c d* are repeated across the fabric, and the twilled pattern is composed of ranges of diagonal

lozenges converging to the diamond-shaped centers *f g h*. These stripes and diagonal lozenge patterns produce a peculiar ornamental appearance in this class of carpets, and the same is not dependent upon any particular colors employed in the stripes.

I claim as my invention—

The ornamental design for a carpet, consisting in the longitudinal stripes and the diagonal lozenge patterns, substantially as represented.

Signed by me this 15th day of June, 1883.

FREDERICK BEND.
